UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

ANTENNA-CIRCUIT ARRANGEMENT.

Original application filed August 19, 1921, Serial No. 493,666, and in France November 11, 1915. Divided and this application filed September 25, 1923, Serial No. 664,681. Renewed June 23, 1926.

(GRANTED UNDER THE PROVISIONS OF THE ACT OF MARCH 3, 1921, 41 STAT. L., 1313.)

This application is a division of my application Serial No. 493,666, filed August 19, 1921, for antenna circuit arrangements.

In circuit arrangements suggested in the past for supplying current to radio telegraphic antenna with cathodic generators the antenna-ground circuit is influenced in accordance with the known methods either by induction or branch connections under the control of a local oscillatory 10 circuit associated with the generator.

By connecting together the two circuits, antenna-ground and the oscillatory circuit, two wave lengths may be obtained in the 15 antenna.

It is the object of the present invention to eliminate the phenomena whereby two waves are sent out.

In accordance with the present invention 20 the antenna circuit is connected directly into one of the circuits of the generator, whereby a single oscillatory circuit is obtained.

Referring to the accompanying drawing the circuit diagram therein shown illustrates 25 an embodiment of this invention. The antenna A is connected to the end of an inductance coil forming one of the windings of a transformer T. An additional inductance L and a condenser C are connected in 30 series with the winding T and the antenna A—one terminal of the condenser C being grounded. An auxiliary inductance E is connected in parallel with the condenser C for the purpose of permitting the passage 35 of direct current from the source X into the cathodic generator. The value of this inductance should be sufficiently high so that it will under no circumstances be traversed by the high frequency current, in 40 order to prevent the formation of an oscillatory circuit E, C. Preferably the inductance is provided with an iron core, whereby it will not occupy much space. The cathodic generator D comprises a plate P which 45 is connected to one terminal of the source X, a grid G and a filament F. Between the grid and plate there is inserted one winding of the transformer T. It is through this 50 transformer that energy is fed back from the plate-filament circuit to the grid-filament circuit whereby oscillations are generated. In the arrangement described the only tuned

circuit is the antenna-ground circuit including the antenna A, inductance L, capacity C and one winding of the transformer T all 55 connected in series. The circuit also includes the capacity between the antenna and ground. The frequency to which this circuit is tuned determines the frequency to which the whole circuit is tuned. 60

The circuit arrangement described may be used either as a transmitter or as a regenerative receiver. If used as a transmitter the circuit would of course be adjusted to oscillate and if used as a receiver it could 65 be adjusted to operate regeneratively just below the oscillating stage. In the case of heterodyne reception it could be adjusted to oscillate while receiving. These adaptations are of course well understood by those skilled 70 in the art and for that reason it is unnecessary to show any means either for producing audible signals or for indicating such signals.

Having described my invention, what I 75 claim is:

1. In a signalling system, a thermionic device having a filament, a plate and a grid, an input circuit including an inductance connected between said grid and said filament, an output circuit including a source of electromotive force, and an impedance coil connected between said plate and said filament, a condenser connected in shunt of said impedance, an antenna connected to 80 said output circuit, said antenna including a second inductance coupled to said first mentioned inductance, and a ground connection for said plate circuit. 85

2. In a signaling system, a thermionic 90 device having a filament, a plate and a grid, an input circuit including an inductance connected between said grid and said filament, an output circuit including a source of electromotive force and an impedance coil 95 provided with a magnetic core, said output circuit being connected between said plate and said filament, a condenser connected in shunt of said impedance, an antenna connected to said output circuit, said antenna including a second inductance coupled to said first mentioned inductance, and a ground connection for said plate circuit. 100

3. In a signaling system, a thermionic

device having a filament, a plate and a grid, an input circuit including an inductance connected between said grid and said filament, an output circuit including a source 5 of electromotive force, and an impedance coil connected between said plate and said filament, a condenser connected in shunt of

said impedance, an antenna connected to said output circuit at a point between said plate and said impedance, said antenna including 10 a second inductance coupled to said first mentioned inductance, and a ground connection for said plate circuit.

MARIUS LATOUR.
